MEANS FOR CONTROLLING AND REVERSING SHIPS PROVIDED WITH PROPELLERS

Filed March 28, 1923

UNITED STATES PATENT OFFICE.

SIDNEY GOLDEN, OF ALTRINCHAM, ENGLAND, ASSIGNOR TO GEORGE FLINDERS JARVIS, OF LONDON, ENGLAND.

MEANS FOR CONTROLLING AND REVERSING SHIPS PROVIDED WITH PROPELLERS.

Application filed March 23, 1923. Serial No. 628,279.

To all whom it may concern:

Be it known that I, SIDNEY GOLDEN, a subject of the King of Great Britain and Ireland, residing at Altrincham, in the county of Chester, England, have invented certain new and useful Improvements in Means for Controlling and Reversing Ships Provided with Propellers, of which the following is a specification.

10 This invention relates to improvements in means for controlling and reversing ships provided with propellers whereby all manoeuvering both ahead and astern, can be carried out with the propeller turning in the 15 ahead direction without modifying its revolutions.

According to this invention, a tubular body is mounted to swing about a substantially vertical axis intersecting the axis 20 of rotation of the propeller, and to enclose the wake thereof, the said body acting normally as the rudder and being provided with means to form an adjustable abutment therein at will for partially or wholly 25 arresting the wake, whereby the direction of the wake can be reversed or partially reversed, and be directed forward for movement directly astern, or directed to port or starboard for steering while going astern. 30 Moreover, by balancing the wake so that half goes astern and half ahead, the ship will remain stationary assuming there to be no current, and can be turned on its centre by giving it helm.

35 The means for forming the abutment, comprises a plate pivoted diametrically inside the tubular body behind the propeller in the manner of the movable valve element of the "butterfly" type of valve.

40 The tubular body forms the rudder or manoeuvering tube and preferably surrounds the propeller at its forward end, and the sides at this end are preferably splayed or flared outward in a horizontal 45 plane, so that the astern end may be somewhat contracted in area. The valve lies normally in a feathering position in the wake of the propeller, from which position it is allowed an angular movement of about 50 ninety degrees and it can be fixed at different angles within this range so that the passage through the tubular body can be varied in area from full bore to total closure. The valve is operated and fixed in 55 the desired positions, from inside the ship

by means of any suitable mechanism either manually or by power and in such a way that there is no interference with the freedom of giving the ship helm.

The accompanying sheet of drawings, 60 shows how my invention may be carried out. Figure 1 represents the stern end of a boat fitted with my invention, in side elevation; Figures 2 and 3 representing end elevation and plan respectively. Fig- 65 ure 4 represents the improved rudder, rudder-stock and valve or abutment in sectional elevation upon an enlarged scale. Figures 5 and 6 represent the rudder and valve in sectional elevation with the valve 70 in two different positions. Figures 7 and 8 are diagrammatic views in plan, of modifications in the disposition and manner of operating the valve.

Referring to Figures 1 to 6 of the draw- 75 ings—the tubular body or rudder casing 1 is shown cylindrical at the astern end 2 but forward is splayed or flared at the sides as seen at 3, Figures 2 and 3, by which the casing may be smaller in average cir- 80 cumference while still providing sufficient clearance at the sides to allow the wake when reversed, to pass out more freely forward. The part of the casing forward of the axis of the rudder stock is suitably 85 proportioned in length to that part aft of the rudder stock, in order to efficiently balance the rudder. The rudder casing may be indented at one or at each end at the top and bottom as indicated at 4, see Figure 3, 90 mainly in order to reduce weight.

The "butterfly" valve 5 is mounted to turn on a horizontal axis 6 as shown, the pivots 7 being secured to the valve in any suitable way. The journal bearings are in- 95 dicated by 8. The axis of the valve is kept as far forward as will allow of just sufficient freedom of movement when the valve is in its normal position. In the drawings, the valve is shown as just fitting the casing 1 100 and adapted to close the passage through when it is vertical with the axis of the casing, and stops 9 are provided to limit its movement. The valve may however be made to fit and close the passage by edge con- 105 tact with the casing in the usual manner of the "butterfly" valve. A suitable forked lug such as 10 Figures 2, 4, 5 and 6, may be secured to the valve for the connection of the operating device.

The rudder stock is indicated by 11 and in the case illustrated in Figures 1 to 6, is tubular. A sliding core or rod 12 passing down the hollow stock 11, is employed to 5 operate the valve. The lower end of the core slides in an annular guide 13 at the bottom and carries an arm 14 rigidly fixed to it, the arm having a slot 15 in the end and passing through the lug 10, a bolt 16 and 10 or the like connecting the two parts together.

The lower end 17 of the annular guide, forms the bottom pintle of the rudder.

The rudder stock is turned in the usual 15 way. As shown, a tiller 18 is fixed to the stock 11 and at the inner end of the tiller is carried a bell-crank lever 19 with forked end 20 which embraces a collar 21 fixed to the sliding core 12. The bell-crank lever 19 20 is connected to a hand lever 22 pivoted to the free end of the tiller at 23, by means of the coupling rod 24. A notched sector 25 is also fixed to the tiller so that the hand lever can be held at definite points corresponding to 25 different angular positions of the valve. Any other suitable known mechanism may be employed for operating the valve from the head of the stock in place of that shown in the drawings.

30 If the valve 5 were arranged vertically, obviously the core 12 would require to be turned instead of being slid as the operating arm 14 would require to move angularly. This modification is shown diagrammatically in plan in Figure 7.

In place of a core 12, a tubular shaft 26 may enclose or surround the rudder stock and a lever arm 27 may be fixed thereto at the lower end and another arm 28 fixed to 40 the pivot 7 of the valve outside the casing, see diagram in plan in Figure 8.

The horizontal position of the valve shown in Figure 4, is the normal one, that is to say, the valve is in a feathering position in 45 relation to the wake and functionally inoperative.

In Figure 3 the valve is shown at an angle of about forty-five degrees. The actual position of the valve to cause the ship to pull up and remain stationary would be in the neighbourhood of this angle, probably several degrees less in many cases; the best position would have to be found by trial. By varying the angle of the valve on each side of 55 this neutral line, both the forward and astern speeds of the ship can be modified without varying the speed of or reversing the propeller. Figure 6 shows the position of the valve for full speed astern.

60 In cross section, the tubular body may be circular, elliptical or elongated, or rectangular for the full length or for part of its length only. For instance, the after part of the tubular body may be rectangular or in 65 the form of a regular polygon, while the

forward part may be either polygonal, circular or of a somewhat elliptical form as shown in the drawings.

I claim:

1. A ship provided with a propeller, a reversing and controlling means comprising a tubular body mounted to swing about a substantially vertical axis intersecting the axis of rotation of the propeller and to enclose the wake thereof said body being splayed laterally at the forward end thereof and a "butterfly" type of valve element behind the propeller and pivoted to the sides of said body inside with the pivots thereof in a horizontal plane, said valve element being mounted so as to swing from a feathering position in the wake of the propeller into an approximately vertical position relative to the axis of the tubular body and adapted to completely close the passage 85 through said body to the wake of the propeller and stops to prevent said valve element from passing beyond said feathering and vertical positions, and means operated from inside the ship for swinging said valve element and holding it in any desired angular position in the arc through which it can move.

2. A ship provided with a propeller, a reversing and controlling means comprising a tubular body mounted to swing about a substantially vertical axis intersecting the axis of rotation of the propeller and to enclose the wake thereof and a valve element of the "butterfly" type pivoted in said body 100 and adapted to form an adjustable abutment behind the propeller so as to partially or wholly close the passage through said body to the wake of the propeller, and means for turning said valve on its axis from inside 105 the ship, comprising a shaft concentric with the rudder post and having an independent motion, the lower end of said shaft being pivotally connected to said valve element through lever arms, and the upper end 110 thereof being movable relatively to said rudder post by means of mechanical elements connected with the manual controlling device.

3. A ship provided with a propeller, a reversing and controlling means comprising a tubular body mounted to swing about a substantially vertical axis intersecting the axis of rotation of the propeller and to enclose the wake thereof, said body being 115 splayed laterally at the forward end, and a valve element of the "butterfly" type adapted to form an adjustable abutment in said body behind the propeller so as to partially or wholly close the passage there-through to the wake of the propeller, and means operated from inside the ship for adjusting said valve element into a full or a partially feathering position or into a full 120 or a partially wake arresting position com- 130

prising a shaft concentric with the rudder post and having an independent motion the lower end of said shaft being pivotally connected to said valve element through lever 5 arms, and the upper end thereof being movable relatively to said rudder post by means of mechanical elements connected with the manual controlling device.

4. The combination with a rotatable

manoeuvering tube and its hollow rudder stock, of a valve plate pivoted within the tube, a rod slideable in the stock and supported in said tube, a fixed arm on the rod, and an operative connection between said arm and valve plate, and means for reciprocating said rod.

SIDNEY GOLDEN.
